Attorney

UNITED STATES PATENT OFFICE.

JAMES B. GURNEY, OF COLLINSVILLE, ALABAMA.

PENCIL SHARPENER.

Application filed October 8, 1925. Serial No. 61,254.

This invention relates to pencil sharpeners, and has for one of its objects the provision of a novel, simple and highly efficient lead pointing attachment for pencil sharpeners of the various types now on the market.

With the foregoing and other objects in view, the invention consists in the construction, combination and arrangement of parts hereinafter fully described and claimed, and 10 illustrated in the accompanying drawing, wherein:

Figure 1 is a top plan view of a pencil sharpener embodying my invention,

Figure 2 is a view in side elevation of the 15 pencil sharpener,

Figure 3 is a view in end elevation of the pencil sharpener,

Figure 4 is a transverse sectional view taken on the plane indicated by the line 4—4 20 of Figure 2,

Figure 5 is a longitudinal sectional view taken on the plane indicated by the line 5—5 of Figure 1, and

Figure 6 is a similar view taken on the 25 planes indicated by the line 6—6 of Figure 5.

Corresponding and like parts are referred to in the following description, and designated in the several views of the accompanying drawing, by similar reference characters.

30 The device comprises a body 1 provided with recessed top, bottom and lateral sides 2, 3 and 4, respectively. The bottom side 3 is provided with longitudinally extending ribs 5 to permit the device to be readily held 35 against movement during the sharpening of a pencil. The body 1 is provided with a conical bore 6 which extends longitudinally thereof, and is provided in one of its lateral sides 4 with a longitudinally extending slot 7 which registers with the bore 6. A blade 8 40 is secured to the side 4 in which the slot 7 is located, and the cutting edge thereof enters the bore 6 through said slot. The blade 8 is recessed into the bottom wall of the side 4 and is secured in place by a cap screw 9.

The body 1 is provided with a second conical bore 10 which is considerably smaller transversely than the bore 6 and is located adjacent the side 2. The bore 10 extends longitudinally of the body 1, and the side 2 is provided with a longitudinally extending slot 11 which communicates with and extends throughout the entire length of the bore 10. A blade 12 is recessed in the side 2 and is secured in place by a cap screw 13. The cutting

edge of the blade 12 extends through the slot 11 into the bore 10.

The body 1 is provided with a recess 14 which extends from the top side 2 to the bottom side 3 and which opens out through said sides and end of the body.

A lead pointing attachment which comprises a block 15, a casing 16 and blades 17, is secured in the recess 14 by a cap screw 18. The bottom wall of the recess 14 inclines downwardly and forwardly so as to support the lead pointing attachment in a downwardly and forwardly inclined position.

The blades 17 have a downwardly convergent relation, and the cutting edges of the blades and that portion of the casing 16 directly opposite said edges also have a downwardly convergent relation.

The upper and lower ends of the casing 16 are open, and the sides thereof are provided with openings 19 through which the cuttings

of the lead discharge. The block 15 is provided at its lower end with a downwardly extending lug 15^a through which the block attaching screw 18 passes.

The rear portion of the casing 16 surrounds the block 15, and these parts may be welded or secured together in any other suitable manner.

The blades 17 are carried by the block 15, and they are secured to the block by having their rear portions embedded in the block.

When it is desired to sharpen a pencil of the average size, the pencil is placed in the bore 6 and rotated against the cutting edge of the blade 8. A smaller pencil may be sharpened by placing it in the bore 10 and rotating it against the cutting edge of the blade 12.

The lead of the pencil may be pointed by inserting it in the upper end of the casing 16 and rotating the pencil in opposite directions against the cutting edges of the blades 17.

If desired, the end of the lead of a pencil may be sharpened by rotating it against the cutting edge of but one of the blades 17. If, however, the point of the lead is rotated first against one and then against the other of cutting edges of the blades 17, the point of the lead may be sharpened in a comparatively short time.

The lead pointing attachment may be used in connection with pencil sharpeners of types other than the type shown in the drawing.

While I have described the principle of operation of the invention, together with the device which I now consider to be the best embodiment thereof, I desire to have it un-

derstood that the device shown is merely illustrative, and that such changes may be made when desired as are within the scope of the invention as claimed.

• What is claimed is:—

10 A device of the character set forth, comprising a body provided with a recess opening out through an end and opposite sides thereof, a casing having a portion thereof positioned in the recess in contact with the bottom and side walls of the recess, a block arranged within and secured to said portion of the cas-

ing and provided at one end with a lug extending beyond the casing, a block attaching screw passing through the lug and engaging the body, and blades arranged within the casing between the remaining portion thereof and the block, the blades being angularly related and having portions thereof embedded in the block, and the cutting edges of the 20 blades and that portion of the casing directly opposite said edges being angularly related.

In testimony whereof I affix my signature.

JAMES B. GURNEY.
